J. N. DIDAY

HINGE

Filed May 18, 1925

UNITED STATES PATENT OFFICE.

JESSE N. DIDAY, OF COLUMBUS, OHIO, ASSIGNOR TO THE BELMONT CASKET COMPANY,
OF COLUMBUS, OHIO, A CORPORATION OF OHIO.

HINGE.

Application filed May 18, 1925. Serial No. 30,897.

To all whom it may concern:

Be it known that I, JESSE N. DIDAY, a citizen of the United States, residing at Columbus, in the county of Franklin and State 5 of Ohio, have invented certain new and useful Improvements in Hinges, of which the following is a specification.

This invention relates to improvements in hinges, particularly those applied to caskets 10 and similar articles, wherein the lid is hinged in a manner to be readily detached from the body of the casket by swinging the lid to an abnormal position.

The object is to construct a hinge that will 15 permit a lid to be closed snugly upon the body of the casket, and for all normal uses permit the lid to be opened to a position substantially at right angles to the body without detaching or disarranging the leaves of 20 the hinge, but by swinging the lid beyond the right angular position the lid can readily be detached from the casket. It is customary 25 in manufacturing metal caskets to assemble the parts together and thereafter upholster or line the body of the casket and lid and for that reason it is desirable to detach the lid from the casket.

This improvement is shown applied to a 30 butt hinge wherein the leaves of the hinge have the knuckles and pintle at the inner edges of the leaves, but applicant does not 35 wish to limit the invention to that particular type of hinge.

Referring to the drawings, Fig. 1 is a 35 longitudinal section, parts being broken away and the lid being shown closed in full lines and in open position in dotted lines. Fig. 2 is a detail view in section, the parts 40 being in closed position. Fig. 3 is a similar view, the lid being in abnormal position for purposes of disconnecting same. Fig. 4 is a perspective view showing the leaves of the hinge disconnected.

Like figures of reference indicate like parts 45 throughout the different views.

The body of the casket is marked 1 and the lid is 2. The hinge is composed of the leaves 3 and 4. The leaf 3 of the hinge is formed with the usual knuckles 5 and 6 50 through which the pintle 8 is inserted and

this leaf is preferably secured to the casket with the pintle projecting below the top surface of the body of the casket as indicated in Figs. 1 and 2. The leaf 4 is preferably secured to the lid and has a hook shaped part 55 7 at its inner end and this hook shaped part 7 is adapted to fit over the pintle 8 and between the knuckles 5 and 6 and as indicated in Figs. 2 and 3, the hinge members are so formed and the parts thereof so arranged that in open position the leaves will be offset one from the other and in closed position the leaves will make a snug fit one upon the other. The braces or hinged holding bars 9 will keep the lid from swinging 60 to a position where the lid can be detached from the body of the casket, but by removing the braces 9 the lid can then be swung to the position shown in Fig. 3 when the hook shaped part 7 can be removed from 65 engagement with the pintle, thereby removing the lid from the casket, but in the positions shown in Fig. 1 the hook can not be removed from engagement with the pintle by 70 reason of the free end of the hook being 75 clamped between the pintle 8 and the inner edge of the leaf 3. In this manner there is formed a hinge that is adapted to a lid that must be closed with a snug fit and yet one that can be readily removed when 80 thrown into an abnormal position.

Having described the invention, I claim as follows:

Hinging devices for the top of a receptacle in which the top is capable of dropping by gravity consisting of a plurality of 85 hinges for the top, each hinge comprising a pair of leaves, one of said leaves having a pair of spaced-apart knuckles and the other leaf having a knuckle registering with the 90 space between the knuckles of the other leaf, a pintle for said knuckles, said single knuckle being laterally offset with relation to its leaf and open at one side to permit it to be lifted from said pintle when the lid 95 is in open position, the opposing leaves being formed to prevent the disconnection of said open knuckle from said pintle during the normal swinging movement of said top, means for limiting the normal swinging 100

movement of said top but capable of being released to permit the top to make an abnormal movement for the purpose of disconnecting the open knuckle from said pintle, the offset relation of said open knuckle with respect to its leaf permitting the top to close tightly against the receptacle while permitting the hinge members to remain locked

during normal movement of the top and to be disconnected by a lifting movement of the top from the receptacle after an abnormal movement of the top.

In testimony whereof, I have hereunto set my hand this 14th day of May 1925.

JESSE N. DIDAY.
